Patented June 10, 1958

183,003

RIDING POWER LAWN MOWER

Arthur L. Kaeser, Springfield, Ohio

Application December 17, 1956, Serial No. 44,212

Term of patent 14 years

(Cl. D40—1)

Fig. 1

Fig. 4

Fig. 1 is a perspective view of one side of a riding power lawn mower embodying my new design;

Fig. 2 is a perspective view of the other side thereof;

Fig. 3 is a top view thereof; and

Fig. 4 is a rear end view thereof.

I claim:

The ornamental design for a riding power lawn mower, substantially as shown.
